UNITED STATES PATENT OFFICE.

EDWIN H. HAWLEY, OF WASHINGTON, DISTRICT OF COLUMBIA.

AUTOMATIC GAS-EXTINGUISHER.

1,088,987.

Specification of Letters Patent.

Patented Mar. 3, 1914.

Application filed November 20, 1913. Serial No. 802,087.

To all whom it may concern:

Be it known that I, EDWIN H. HAWLEY, citizen of the United States, residing at Washington, in the District of Columbia, 5 have invented certain new and useful Improvements in Automatic Gas-Extinguishers, of which the following is a specification.

This invention relates to gas burners, and its object is to prevent the escape of gas in 10 case the flame is extinguished without turning off the cock.

To this end it consists in a thermostatic device attached to the gas burner, which sets a trigger when the gas is lighted, said trigger 15 engaging with detents on the stop cock of the burner and holding it open until the trigger is tripped by the cooling of the thermostatic device upon the extinguishing of the flame. When this occurs, a spring or 20 equivalent element closes the stop cock.

I am aware that in its broad aspects this invention is not new. My invention is therefore limited to a specific form of that class of thermostatic devices in which the expansion 25 of air is utilized to operate the stop cock. Air does not deteriorate by repeated heating and cooling, and its container can be made of such a shape that it will cool quickly and thus cause a prompt action of 30 the closing mechanism.

Various modes of carrying my invention into effect may be devised, but I prefer the specific construction shown in the accompanying drawing, in which—

35 Figure 1 is a side elevation, partly broken away, of a gas burner equipped with my improved automatic closing device. Fig. 2 is a sectional elevation of the stop cock. Figs. 3, 4 and 5 show the spindle of the stop cock in 40 three different positions.

The stop cock is of the ordinary variety, having a tapering plug 1 fitting a socket in a casing 2, said plug having a passage 3 for the gas which can be made to register with 45 the longitudinal passage 4 in the casing. The smaller end of the plug in my stop cock is turned down to receive a drum 5 which is secured in place by a screw 6 tapped into the end of the plug. Means for 50 rotating the plug to its closed position are applied to this drum, preferably a coiled spring 7 having one end attached to said drum and the other to a stud 8 projecting from the casing. A stop 9 on the plug 55 strikes a shoulder 10 on the casing when the plug reaches its closed position. On the

plug are mounted two catches 11 12 set in different planes of revolution and angularly spaced apart.

A base 13 is erected on the casing 2 having a passage 14 for the gas which terminates in a suitable tip 15. From said base rise standards 16 which support the air chamber 17. This is preferably annular to let the hot gases pass up through it, and is 60 preferably somewhat like a frustum of a cone, with curved walls affording large heating and cooling surfaces. The chamber is preferably spun up out of thin sheet metal, such as copper. The upper ends of the 65 standards 16 are secured to a flange 18 at the lower edge of the chamber, and this may be reinforced by a ring 19 if desired. The chamber is held at such a height above the tip 15 as not to obstruct the light from the 70 frame, but near enough to be quickly heated thereby. From one side of the air chamber 75 17 projects a horn 20 whose mouth is closed by a thin flexible diaphragm 21 of sheet metal, and in order to make the joints of the 80 chamber, horn and diaphragm air tight the entire structure is electroplated with copper after it is made up.

A bracket 22 is secured to the flange of the air chamber and serves as the fulcrum, for 85 a lever 23 whose upper end carries a set screw 24 located opposite the middle of the diaphragm 21. The lower end of the lever has a limited play in a guide 25 attached to the base 13. It terminates in the vicinity 90 of the catches 11 12 and operates as a trigger to release the stop cock in a manner now to be described.

The weight of the trigger tends to keep it in the position shown in full lines, with 95 its lower end in line with the catch 11. When the stop cock is turned to let on the gas, the catch 11 strikes the trigger and pushes it inwardly by reason of the beveled surfaces on the catch and trigger. As soon as the catch passes the trigger, the latter drops back into place and prevents the stop cock from being rotated by its spring. This condition of things is shown in Figs. 2 and 3. The heat of the gas flame soon causes the 100 air in the chamber 17 to expand and push the diaphragm 21 out to the dotted line position. The diaphragm comes in contact with the set screw 24 and forces the upper end of the trigger outwardly. This swings 105 the diaphragm 21 to the dotted line position. The diaphragm comes in contact with the set screw 24 and forces the upper end of the trigger outwardly. This swings 110 its lower end inwardly, as shown in dotted lines, taking it out of engagement with the 115

catch 11 and bringing it into line with the catch 12. The spring 7 attempts to turn the stop cock when the catch 11 is released, but the trigger engages the catch 12 and permits 5 only a slight angular movement of the cock. The position of the parts is shown in Fig. 4, and is maintained so long as the gas is burning. Now, if the flame is accidentally extinguished without shutting off the gas, 10 the rapid cooling of the air chamber allows the diaphragm to return to its normal position, and this permits the trigger to swing outwardly and release the catch 12, whereupon the spring instantly rotates the stop 15 cock to its closed position (Fig. 5). By means of the set screw 24 the action of the parts can be readily adjusted.

It will be seen that in my device there are no soldered or brazed joints to be ruined 20 by the heat of the flame; there are no unwieldy thermostatic strips or bars to become burned out; no operative parts that are slow to respond to changes in temperature. My device will shut off the gas in 25 fifteen or twenty seconds after the flame is extinguished, and is not injured by repeated heatings and coolings.

In accordance with the provisions of the 30 patent statutes, I have described the principle of operation of my invention, together with the apparatus which I now consider to represent the best embodiment thereof, but I desire to have it understood that the apparatus shown is only illustrative and that 35 the invention can be carried out by other means.

What I claim and desire to secure by Letters Patent is:—

1. The combination with a gas burner having a self closing stop cock, of an annular 40 air chamber located above said burner and arranged to be heated by the gas flame and having a flexible portion, and a trigger adapted to be operated by said flexible portion and thereby release the stop cock. 45

2. The combination with a gas burner having a self closing stop cock, of an annular air chamber made of thin sheet metal and located above said burner, a flexible diaphragm carried by said chamber, and a trigger 50 arranged adjacent to said diaphragm and operating to release said stop cock.

3. The combination with a gas burner having a self closing stop cock, of an annular air chamber made of thin sheet metal and 55 located above said burner, a horn projecting from said chamber, a flexible diaphragm closing the mouth of said horn, and a trigger having one end adjacent to said diaphragm and operating to release said stop 60 cock.

4. The combination with a gas burner having a self closing stop cock, of an air chamber composed of thin sheet metal, said chamber being annular in shape and resembling 65 a frustum of a cone, with curved walls.

In testimony whereof I affix my signature in presence of two witnesses.

EDWIN H. HAWLEY.
